UNITED STATES PATENT OFFICE.

WILLIAM K. ATWOOD, OF PROVIDENCE, RHODE ISLAND.

DESIGN FOR WATCH CHAIN AND CHARM.

Specification forming part of Design No. **11,323**, dated August 5, 1879; application filed May 19, 1879.
[Term of patent 7 years.]

To all whom it may concern:

Be it known that I, WILLIAM K. ATWOOD, of the city and county of Providence and State of Rhode Island, have originated a new and useful Design for a Vest Chain and Charm, of which the following is a full, clear, and exact description, reference being had to the accompanying drawing, forming a part of this specification.

My design is composed, in whole or in part, of implements employed in the game of base-ball, the essential elements being a miniature bat, a miniature belt, and a miniature ball, and these may be combined to form a vest chain and charm, as shown in the drawing, where A denotes the chain and B the charm.

The bats *a*, belts *b*, and balls *c* may be arranged with reference to each other to form a chain, as illustrated, the said parts being connected by links. These links as to number or shape, however, form no essential part of my design; neither do I confine myself to the exact relative arrangement shown of the essential elements.

With the above-mentioned essential elements of my design other parts may be combined—as, for instance, caps, as shown at *d* in the drawing, or other parts of the paraphernalia of a base-ball field.

The bats *a*, belt *b*, and ball *c* also form the essential elements of the charm B, which is attached to the chain by links, and is provided with a seal, *e*. The links and seal, however, are not essential portions of the design, neither is the shoe *f* or diamond *g*, although the same, as well as other parts, may be combined with the essential elements—a bat, a belt, and a ball—to form the charm.

Having described my invention, what I claim, and desire to secure by Letters Patent, is—

1. The design for a watch-chain consisting essentially of the representation of the bat *a*, belt *b*, and ball *c*, substantially as described, and shown in the accompanying drawing.

2. The design for a watch-chain charm consisting essentially of the bat *a*, belt *b*, and ball *c*, substantially as described, and shown in the accompanying drawing.

3. The design for a watch chain and charm consisting essentially of the bat *a*, belt *b*, and ball *c*, substantially as described, and shown in the accompanying drawing.

WILLIAM K. ATWOOD.
